DESCRIPTION

(52) **U.S. Cl. D23/238**

A water faucet with dials and a display to control water volume and temperature. The faucet has hot and cold water controls similar to a regular water faucet. In addition, two dials are included on the top side of the faucet to allow a user to turn forward and backward to make adjustments. Towards the front of the top side is a display. The display indicates the temperature water temperature and water volume rate.
